UNITED STATES PATENT OFFICE

WALTER P. MURPHY, OF CHICAGO, ILLINOIS.

METAL CAR-DOOR.

1,163,028.

Specification of Letters Patent.

Patented Dec. 7, 1915.

Application filed February 13, 1914. Serial No. 818,486.

To all whom it may concern:

Be it known that I, WALTER P. MURPHY, a citizen of the United States, residing at Chicago, in the county of Cook and State 5 of Illinois, have invented certain new and useful Improvements in Metal Car-Doors, of which the following is a specification.

The object of my invention is to provide an all metal door, adapted for wooden and 10 all metal cars, of a simple, durable and economical construction and which may be readily and economically repaired; and with these and minor objects in view my invention consists of the parts and combination 15 of parts as will be hereinafter fully set forth.

In the drawings:—Figure 1 is a front elevation of an all metal car door embodying my invention; Fig. 2 an end elevation of the 20 same; Fig. 3 is a vertical sectional view of my door on the line A—B, Fig. 1, showing the door in position on a car; Fig. 4 is an enlarged detail sectional view on the line C—D, Fig. 1; Fig. 5 is an enlarged detail 25 sectional view showing a modified form of joint between the plates.

My improved car door is composed of a plurality of sections or plates 6, 7, 8 and 9 each being substantially triangular in outline. 30 Two side marginal edges of each plate are rebent at right angles to the plane of the plate to form a flange 10 which gradually increases in height from the outer edge toward the center of the plate, as more clearly 35 shown in Figs. 2 and 3. When the flanges 10 of abutting plates are brought together and riveted by means of the rivets 11, with a weatherproof joint, they constitute, in effect, a truss, or compression member which 40 very materially strengthens the door to withstand thrusts due to shifting freight, and prevents it from becoming twisted by rough handling. A four way cap 12 is placed over these flanges 10 at the point of 45 intersection to close the joint between them at such point; said cap being secured to the flanges by means of the rivets 13.

The outer edge of each plate is formed with an under open rebend 14 which stiffens 50 said outer edge as will be understood by those skilled in the art of metal working. This open rebend 14 on the upper and lower plates (6 and 8) of the door constitute housings into which the guards 15, on the car,

project whereby the door is prevented from 55 swinging away from the side of the car. 16 are roller castings secured to the bottom plate of the door, the rollers of which run on the track 17, which track is shown integral with the guard 15. 60

18 are corner caps which fit snugly over the corners of the door and over the ends of the upstanding flanges 10; said caps being riveted to said flanges as shown.

Vertical, horizontal and diagonally disposed corrugations are pressed in each plate 65 to reinforce it, the diagonal corrugations, on each plate, intersecting each other.

It will be noted that plates 6 and 8 are duplicates of each other, and that plates 7 70 and 9 are duplicates of each other whereby repairs are facilitated.

From the above it will be seen that I have provided a durable, rigid, compact and economical door and that my improved door is 75 sufficiently subdivided, so that in case of accident, whereby the door is bent or twisted, there will be no difficulty in finding a furnace big enough to effect the needed repairs, which would not be the case when the door 80 is constructed from a single piece of metal. Besides which, in the original manufacture of the door, the subdivided plates are much more easily handled at the press than would be the case with a single sheet the size of 85 the door.

In Fig. 5 I have shown a modified form of joint between the plates wherein the side marginal flange of one side is rebent from the said marginal flange of the adjacent 90 plate, said rebend forming, in effect, a cap for the joint.

What I claim is:—

“A metal door composed of a plurality of sections having upturned marginal abutting 95 edges riveted together, a multiple way cap to receive the cover and be secured to said upturned edges where the joints of the plates cross each other, and caps fitting over corners of the door and the outer ends of the 100 upturned marginal abutting edges of the said sections.

In testimony whereof I affix my signature in presence of two witnesses.

WALTER P. MURPHY.
